UNITED STATES PATENT OFFICE.

WILLIAM EZRA ROSS, OF ROCHESTER, NEW YORK.

REIN-HOLDER.

SPECIFICATION forming part of Letters Patent No. 427,617, dated May 13, 1890.

Application filed February 1, 1890. Serial No. 338,864. (No model.)

To all whom it may concern:

Be it known that I, WILLIAM EZRA ROSS, a citizen of the United States, residing at Rochester, in the county of Monroe and State of New York, have invented a new and useful Rein-Holder, of which the following is a specification.

This invention relates to rein-holders, and is an improvement upon an invention for which 10 an application for Letters Patent, Serial No. 318,285, was filed by me July 24, 1889; and the invention consists of the improved means for operating the movable half-clutch of said application, which means are fully described 15 hereinafter, and illustrated in the accompanying drawings, in which—

Figure 1 is a front view of a buggy with my device attached thereto. Fig. 2 is a rear view of the dash-board of the buggy. Fig. 3 is a 20 detached view of the mechanism for operating the movable half-clutch. Fig. 4 is a cross-section of the tube on line 4 4 of Fig. 2.

Referring to the accompanying drawings, 1 designates the buggy or wagon body, having 25 a dash-board 2, a fifth-wheel 3, a front axle 4, and wheels 5, in the ordinary manner.

6 designates a gear-wheel upon the hub of one or both of the front wheels; 7, a transverse shaft journaled in front of the front 30 axle; 8, a gear-wheel meshing with the gear 6; 9, a stationary half-clutch keyed to said shaft; 10, a movable half-clutch on said shaft; 11, the teeth of said clutches; 12, a spring for keeping the half-clutches normally apart, and 35 13 the drum on the movable clutch, all as shown in my other application above referred to.

14 designates a vertical tube having longitudinal grooves 15, which tube is secured to 40 the inner face of the dash-board. 16 is a pair of clamps sliding in said grooves, and 17 is a strap connected to the lower clamp and passing through a hole 18 in the bottom of the wagon-body, with its lower end connected to 45 and adapted to be wound upon the drum 13 upon the movable half-clutch 10, all substantially as shown and described in my other application referred to.

Coming now to the present invention, the 50 letter S designates a leaf-spring seated at its lower end below a clip C in the interior of the tube 14, and its body being bent out-

wardly, so as to impart a gentle pressure to the clamps 16, whereby they are held frictionally in any desired position. Alongside 55 the tube 14, in suitable eyes I, is mounted a vertical rod R, having a handle or head H at its upper end and a stud or stop r in its body to prevent its displacement. A leaf-spring s is secured to the side of the tube 14, and its 60 body bears gently against the rod R, whereby the latter is frictionally held at any desired height. Connected to the lower end of the rod R is a cord or chain D, which passes downwardly through the bottom of the wagon-body 65 and over a number of pulleys P to the proper point, whence it is led downwardly in rear of the transverse shaft 7 and connected to a cam M. It will be understood that the front axle 4 is provided with a pair of forwardly-projecting bars, within which this transverse 70 shaft 7 is journaled at its ends, and in this bar between the axle and the shaft, on a horizontal longitudinal pin N, is pivoted the cam M, having a curved outer face m and an eye 75 v at its upper corner, to which the cord D is connected. The drum 13 upon the half-clutch 10 has a flange F at its outer end, against which the face m of the cam bears, and from this construction it will be understood that when the rod R within the buggy 80 is raised the cord D will be drawn upon, the cam M turned, and the movable half-clutch 10 thrown into engagement with the stationary half-clutch 9.

In operation this device is substantially the same as my other one referred to—that is to say, when it is desired to hitch the horse the reins are engaged between the clamps 16, which stand normally at the upper end of the 90 tube 14, and the rod R is elevated. The latter motion engages the two half-clutches 9 and 10, and the driver may leave the horse with safety. If now the horse starts, the front wheel will rotate, and the gears will rotate the shaft 7, the two clutches, and the drum 13. This rotation of the drum will draw upon the strap 17, and the clamps 16 will be drawn down in the tube, whereby the reins will be pulled over the upper edge of the dash-board and the bit drawn tightly into the horse's mouth, all as will be clearly understood. To release the device, it is simply necessary to give a slight blow to the head H at the upper 95 100

end of the rod R, which loosens the cord D, permits the cam M to turn, and allows the spring 12 to automatically throw the two half-clutches out of engagement with each other.

5. What I claim is—

1. In a rein-holder, the combination, with the wheel, the transverse shaft having the stationary half-clutch, gearing between the wheel and shaft, a movable half-clutch having a drum, a spring for normally disengaging said half-clutches, a strap connected to said drum and leading to a pair of clamps, and a vertical tube on the inner side of the dash-board, within which said clamps slide, of a cam independent of said strap for throwing said half-clutches into engagement with each other, all substantially as set forth.

2. In a rein-holder, the combination, with the wheel, gears, transverse shaft, stationary clutch, spring-operated movable clutch having a drum, clamps moving in a vertical tube on the inner side of the dash-board, and strap connecting the clamps and drum, of the cam M, bearing against the end of the drum, the cord D, connected with said cam and leading upwardly into the wagon-body, and the rod R, connected to the upper end of the cord, the whole adapted to operate substantially as described.

3. In a rein-holder, substantially as described, the movable half-clutch 10, having the drum 13, in combination with the pivoted cam M, having a curved outer face *m* and an

eye *v* at its upper end, and a cord D, connected to said eye and led into the wagon-body, as and for the purpose set forth.

4. In a rein-holder, substantially as described, the combination, with the drum 13, flange F, cam M, and cord D, of the pulleys P, secured to the bottom of the wagon-body and over which said cord is passed, the vertical and movable rod R within the wagon-body, connected at its lower end to said cord, and means for holding said rod in place, as set forth.

5. In a rein-holder, substantially as described, the combination, with the clamps 16 and the strap 17, connected to a half-clutch, of the vertical tube 14, secured to the inner side of the dash-board and opening at 18 through the bottom of the wagon, the clip C in the interior of the said tube, the leaf-spring S, whose lower end is seated in said clip, and whose body is bent outwardly and bears upon said clamps, tongue-and-groove vertical guides 55 upon the clamps and tube, respectively, a second half-clutch revolved by the wheels, and a cam for engaging said half-clutches, as and for the purpose set forth.

In testimony that I claim the foregoing as my own I have hereto affixed my signature in presence of two witnesses.

WILLIAM EZRA ROSS.
